(57) **CLAIM**

I claim the ornamental design of a closure cap of a measuring apparatus for measuring pool water quality, as shown and described.

DESCRIPTION

FIG. 1 is a perspective view of a closure cap of a measuring apparatus for measuring pool water quality.

FIG. 2 is an end view of the closure cap for the measuring apparatus of FIG. 1.

FIG. 3 is an end view, opposite of the end shown in FIG. 2, of the closure cap for the measuring apparatus of FIG. 1.

FIG. 4 is a bottom view of the closure cap for the measuring apparatus of FIG. 1.

FIG. 5 is a side view of the closure cap for the measuring apparatus of FIG. 1.

FIG. 6 is a top view of the closure cap for the measuring apparatus of FIG. 1; and,

FIG. 7 is a side view, opposite of the side shown in FIG. 5, of the closure cap for the measuring apparatus of FIG. 1.
